Primary Examiner — Amber R Stiles*Assistant Examiner* — Kellianne M Shaver(57) CLAIM

The ornamental design for a goblet as shown and described.

DESCRIPTION

FIG. 1 is a perspective view of a goblet, showing my new design;

FIG. 2 is a front view thereof;

FIG. 3 is a rear view thereof;

FIG. 4 is a left side elevation view thereof;

FIG. 5 is a right side elevation view thereof; and,

FIG. 6 is a top plan view thereof.

The broken lines depict portions of the goblet in which the design is embodied that form no part of the claimed design.

1 Claim, 6 Drawing Sheets(56)
